DESIGN FOR A CASE FOR SPECTACLES

Margaret Ripin, New York, N. Y.

Application November 14, 1942, Serial No. 108,763

Term of patent 3½ years

To all whom it may concern:

Be it known that I, Margaret Ripin, a citizen of the United States, residing at 1225 Park Avenue, in the city of New York, county of New York, and State of New York, have invented a new, original, and ornamental Design for Cases for Spectacles, of which the following is a specification, reference being had to the accompanying drawing, forming part thereof.

In the drawing:

Fig. 1 is a perspective view of a case for spectacles with the front flap slightly turned over to show the lining; and

Fig. 2 is a plan view of the same, showing my new design.

The front face of the case is designed as a half-mask or harlequin-mask and is provided with a lining visible through the cuts representing the eye-holes of the mask. Face and lining respectively are of materials of contrasting colors, as indicated by different shadings.

I claim:

The ornamental design for a case for spectacles, as shown and described.

MARGARET RIPIN.
